UNITED STATES PATENT OFFICE.

GEORGE KING, OF FREDERICK, MARYLAND.

STEP-LADDER.

SPECIFICATION forming part of Letters Patent No. 253,925, dated February 21, 1882.

Application filed November 2, 1881. (No model.)

To all whom it may concern:

Be it known that I, GEORGE KING, a citizen of the United States, residing at Frederick, in the county of Frederick and State of Maryland, have invented a new and useful Improvement in Step-Ladders; and I do hereby declare that the following is a full, clear, and exact description thereof, reference being had to the annexed drawings and letters of reference marked thereon, forming a part of this my specification of said invention, in which drawings—

Figure 1 is a perspective rear view of my improved step-ladder, the same being shown with its hinged swinging support folded down upon the body portion of the ladder. Fig. 2 is a broken detail vertical section in the line $y'y'$ of Fig. 7, showing adjacent and connected upper parts of a top portion of the ladder, on the right-hand side thereof, when viewed from the rear, as in Fig. 1. Figs. 3 and 4 are perspective views of the metal bracket to which the several parts indicated in Fig. 2 are connected. Fig. 5 is an inverted plan view of the left-hand bracket shown in Fig. 1 when looking at the ladder from the rear, as represented in Fig. 1. Fig. 6 is a perspective view of the lock-bar employed to hold the ladder upright in a fixed position when thrown open for use, and Fig. 7 is a broken detail vertical section in the line $y'y$ of Fig. 2.

The main object of my invention is the production of a step-ladder which shall have those bracing portions upon which the greatest strain falls in the act of use thoroughly protected from displacement at the upper ends; and it consists in certain constructions and combinations of parts, hereinafter described and specifically claimed.

In general form my improved step-ladder resembles that for which Letters Patent of the United States were granted me March 28, 1876, No. 175,467, its body portion consisting of side pieces, A A', provided with steps a and a stand-board, a' , in the usual manner. These main pieces A A' are provided on their outer sides with bowing braces B, which extend from the lower end of the side pieces to near the upper end of the same, one of which braces has its entire length indicated in Fig. 1, partly in solid and partly in dotted lines. The lower

ends of these braces are coincident with the lower ends of the side pieces, A A', and thus will stand upon the same foundation as the side pieces when the step-ladder is in position for use, while their upper ends extend up into a socket, b , provided therefor in the metal brackets L L'.

E E are brace-bars, stayed by cross-pieces $e'e^2$, as shown, and with their upper ends seated in a socket, b' , (see Figs. 3 and 5,) of the metal brackets L L', when said brackets are adjusted in position, as signified in Figs. 1, 2, and 7. The construction of the bracket L' is clearly shown by Figs. 3 and 4, in which figures f indicates a main plate extending the whole length of the bracket, f' a plate at right angles to the plate f , as shown, and F a semi-circular cap-bearing, which projects at right angles from the plate f , and is divided by a central plate, as at f^2 , which is perforated at s^2 , thus forming on each side of said central plate an open socket, b and b' , to receive the upper ends of the brace-bars B and E, as shown in Fig. 1. Screw-holes s are made in the plate f to allow the bracket to be screwed in position to the side pieces, A A', while the plate f' has beveled slots s' , through which screws can be passed to confine such plate to the under side of the stand-board a' , as shown. As shown in the figures, the bracket L' is a right-hand bracket, and L a left-hand bracket—that is to say, the bracket L (shown in inverted plan view in Fig. 5) has the cap-bearing F and plate f' on one side of its plate f , while in Figs. 3 and 4 the cap-bearing F and plate f' are upon the other side of the plate f . The brackets L L' are cast of a single piece of metal, and serve as cap-bearings or abutments for the upper ends of the brace-bars E and B, while one side of each upper end of said bars laterally embraces the division-plate f^2 of the brackets, as indicated in Fig. 2, said plate thus assisting to confine the upper ends of the bars B in place, and imparting steadiness of action to the bars E as they swing forward and back upon the confining-bolt M while the step-ladder is in use.

The side pieces, A A', have latch-bars P secured to their outer sides, as indicated in Fig. 1, by bolts passed through a perforation, g , (shown in Fig. 6,) in their rear ends, and upon

which bolts they are made to freely articulate. One of these latch-bars is shown in Fig. 6, its rear end being curved, as at *c c c*, along a portion of its length, as shown, while the remainder of its length to a point, *x*, near its forward end is straight and of the same width, but from the point *x* to its forward terminating end the width of the bar is reduced, as shown, and with one-half of such reduced portion turned up at right angles with the main body of the bar, thus forming a catch, as at *d*, and a shoulder, as at *x'*, so that when the bar *P* is in position, as shown in Fig. 1, and the step-ladder is then thrown open for use, the bar *P* will, during such act, be drawn along through the hasp *P'*, on the inside of the bar *E*, until finally a portion of the rear side of the hasp will engage with the shoulder *x'* of the bar *P*, while a portion of the front side of the hasp will engage with the catch *d*, and thus lock the step-ladder in its open position, ready for use. When it is desired to close up the ladder from its locked open position the bar *P* is raised until its shoulder *x'* becomes disengaged from the hasp *P'*, whereupon the supporting-bars *E* may be closed down, as in Fig. 1, and during this act the bar

P will be projected along through the hasp *P'* until it reaches its position, as shown in said figure, out of the way, and with its main body portion hanging down between the bar *E* and side piece *A'*, which position it is enabled to assume by reason of its rearward bent portion *c c c*.

Having thus described my improved step-ladder, what I claim as new, and desire to secure by Letters Patent of the United States, is—

1. A bracket for step-ladders, cast entire in one piece, with bearing-plates *f* and *f'* and a cap or shoulder bearing, *F*, provided with a partition-plate, *f''*, substantially as and for the purpose described.
2. Swinging braces *E* and braces *B*, in combination with brackets *L* *L'*, provided with separate sockets, *b* *b'*, to receive the upper ends of said braces, substantially as and for the purpose described.

GEORGE KING.
